MANUFACTURE OF ALKYLLEAD COMPOUNDS

Sidney M. Blitzer and Tillmon H. Pearson, Baton Rouge, La., assignors to Ethyl Corporation, New York, N. Y., a corporation of Delaware

No Drawing. Application December 29, 1955
Serial No. 556,051

10 Claims. (Cl. 260—437)

This invention relates to a process for the manufacture of tetrahydrocarbon lead compounds. More particularly, the invention is directed to a new and novel process for the manufacture of tetraalkyllead compounds, of which tetraethyllead is the most important.

The processes heretofore employed on a substantial scale are best illustrated by reference to the production of tetraethyllead. This material is in wide usage as an antiknock agent in the operation of internal combustion engines. The commercial process has generally been highly successful, but has certain inherent disadvantages not heretofore circumvented. The commercial process proceeds by reacting a sodium lead alloy, of composition controlled to correspond substantially to NaPb, with ethyl chloride according to the following equation:

With the highest yields obtained thereby, only some 20 percent of the lead present in the NaPb alloy is converted to tetraethyllead. This conversion of lead to tetraethyllead has not been materially changed in many years, apparently because of an inherent limitation corresponding to the above equation. In this reaction, then, at least 75 percent of the lead originally employed is not alkylated. Large quantities of lead must then be recovered and reprocessed to NaPb alloy in order to make it economical. A further disadvantage of such a large quantity of unreacted lead is that valuable reaction space in the reactor is occupied by materials which are essentially inert for the manufacture of tetraethyllead under present conditions and mode of operation.

Other reaction processes for the production of hydrocarbonlead compounds, especially tetraethyllead, have been devised to consume the lead produced in the above equation. While such processes are satisfactory from the standpoint of lead consumption, they suffer an additional drawback in common with the present commercial process in that they require organo halide as the ethylating agent. One such process is that described in U. S. Patent 2,535,190 wherein lead, as for example that produced in the commercial process, is treated with metallic magnesium and ethyl chloride in the presence of a catalyst, preferably an alkyl ether. Thus, in this process as well as the above mentioned alloy process, the tetraethyllead manufacturing operation is restricted by the necessary balance between the metallic sodium required and the organic chlorine in the ethyl chloride. A classical method for the manufacture of tetraethyllead which likewise requires strict balance between metallic magnesium and organic halide, and has the additional drawback of requiring highly hazardous ether, is the reaction of the so-called Grignard reagent, for instance ethyl magnesium chloride, with lead chloride.

It is an object of the present invention to provide a new reaction process for manufacturing the tetrahydrocarbonlead compounds, the process overcoming the prior difficulties and providing other unanticipated bene-

2

fits. More particularly, an object of the invention is to provide a process which realizes a conversion of lead to tetraethyllead in greater proportions than heretofore provided. Even more specific an object is to provide a process which does not require the use of metallic sodium or other alkali metal. In addition, an object is to provide a process which does not require the use of metallic lead or organic chlorides. A still further object especially of preferred embodiments, is to provide a new reaction process wherein certain lead compounds are reacted with alkyl compounds of active metals.

The foregoing and other objects are attained by the process of reacting a lead organo acid salt and a non-lead alkylmetal compound as an alkylating agent. A substantial number of lead salts as well as of non-lead alkylmetal compounds stable under reaction conditions, are employable, as is illustrated hereafter.

The organic lead salts employed in conducting this invention comprise lead compounds wherein lead is attached to at least one carbon-containing organic radical through an intermediate atom of oxygen or sulfur, that is, a chalkogen. Lead salts of recognized organo acids not having a carboxylic acid grouping, but having strongly acidic hydrogen, are effective in this process. Thus, the lead salts employed in this invention comprise lead carboxylates, lead thiocarboxylates, lead phenates and lead thiophenates. In general, the organic portion of such lead salts comprise alcanoic, cycloalkanoic, carboxylic and phenolic radicals. In a preferred embodiment of this invention a group III-A metal alkylating agent is reacted with a neutral lead salt of an aliphatic carboxylic acid having from one to about 21 carbon atoms in the aliphatic radical. The lead salt employed will be dictated by a number of factors, primarily economics, inasmuch as they all appear to be quite effective in the reaction. The preferred lead compounds are lead salts of low molecular weight carboxylic acids, especially the lead acetates. Another class of organic lead salts particularly suitable in this invention comprise the lead salts of the so-called naphthenic acids having from six to about twenty-five carbon atoms in each organic radical. Additionally, the organic portion of the lead salt can contain other elements besides carbon and hydrogen, in particular oxygen. In those embodiments employing aromatic lead salts, the aromatic radicals can be substituted with other elements including oxygen, nitrogen, sulfur, providing that the substituent is not effective in degrading the metal alkyl reagent.

The alkylmetal reactants used in the process are chosen in accordance with the desired tetrahydrocarbonlead product and may be selected from a large number of materials of high but varying effectiveness. The alkylmetal compounds suitably used are preferably derivatives of a metal having an electrode potential of more than 0.3 volt, including for example group I-A metals such as lithium and sodium, group II metals such as beryllium, magnesium, zinc and cadmium, and group III-A metals such as boron and the aluminum type metals. The fully alkylsubstituted compounds of polyvalent metals are preferred, but alkyl compounds of monovalent active metals, and the partially alkylated derivatives of the polyvalent metals are also suitable.

A particular feature of the process of the invention is the employment of lead organo acid salts to produce tetrahydrocarbon lead, or more particularly, tetraalkyllead products. Such materials have not been heretofore produced from lead organo acid salts. A further unexpected advantage of preferred embodiments of the process of the present invention is the transfer of all the alkyl groups of certain polyalkylmetal alkylating agents reacted, into the tetraalkyllead product.

In preferred embodiments of this invention alkylating compounds having from one to about eight carbon atoms in each alkyl group are reacted with lead salts of aliphatic acids. One such class of lead salts are the lead alkanoates having one to 21 carbon atoms in each acidic radical. Illustrative of such lead salts are lead acetate, lead subacetate, lead tetraacetate, lead butyrate, lead formate, lead oxalate, lead laurate, lead stearate, lead palmitate, lead linoleate, lead propionate, mixtures thereof and the like. Typical of the lead organo acid salts wherein the lead atom is attached to the organic radical through sulfur are lead thioacetate, and lead thioformate. Among the aromatic lead salts which can be employed, typical examples include lead phenate, lead thiophenate, lead phenolsulfonate, lead salicylate and the like. Still other lead salts suitable for practicing this invention include the lead naphthenates and lead resins.

In general, the alkylmetal reactants of the reactions of the process are those organo metalics as already described, having attached thereto at least one alkyl group containing from one to eight carbon atoms. Among the highly effective alkylmetal compounds employable in the reaction are the partly or fully alkyl substituted compounds of aluminum-type metals, viz., aluminum, gallium, and indium in group III-A of the periodic table, the alkylaluminum reactants being particularly preferred. From this group, preferred embodiments include the trialkylaluminum compounds having a total of 3 to 24 carbon atoms in the alkyl radicals, the alkyl radicals being normal or branched chain groups. Among the group III-A metal alkyl compounds which can be reacted with the lead organo acid salts are trimethylaluminum, triethylaluminum, methyldiethylaluminum, tripropylaluminum, dimethylhexylaluminum, methylethyloctylaluminum, triisooctylaluminum, diethylaluminum hydride, methylaluminum dihydride, triisobutylaluminum, diisobutylaluminum hydride, octylaluminum dihydride, sodium aluminum tetraethyl, lithium-aluminum tetraethyl, potassium-aluminum triethyl hydride, sodium aluminum tetrabutyl, potassium aluminum dioctyl dihydride, dimethylaluminum chloride, ethyl-aluminum dichloride, ethylaluminum sesquichloride, trimethylgallium, triethylgallium, methyldiethylgallium, tripropylgallium, dimethylhexylgallium, methyl-ethyloctylgallium, trioctylgallium, dipropylgallium hydride, methylgallium dihydride, triisobutylgallium, diisobutylgallium hydride, sodium gallium tetraethyl, lithium gallium tetraethyl, potassium gallium triethyl hydride, sodium gallium tetrabutyl, caesium gallium dioctyl dihydride, dimethylgallium chloride, ethylgallium sesquichloride, trimethylindium, triethylindium, methyl-diethylindium, tripropylindium, dimethylhexylindium, methyl-ethyloctylindium, trioctylindium, dimethylindium hydride, methylindium dihydride, triisobutylindium, diisobutylindium hydride, sodium indium tetraethyl, lithium indium tetraethyl, potassium indium triethyl hydride, sodium indium tetrabutyl, potassium indium dioctyl dihydride, dimethyl indium chloride, ethyl indium sesquichloride, and the like.

A further highly effective class of alkylating reactants for the process are the alkylzinc compounds, as well as certain other alkylcompounds of divalent metals. Both mono- and dialkyl derivatives are suitable, but the most efficient process employs a dialkylzinc compound, each alkyl group having, preferably, at least one and up to eight carbon atoms. Also among the suitable alkylating agents are the alkyl zinc hydrides, alkyl-zinc halides, and mixtures thereof. Further, the alkyl zinc may be in the form of a bimetallic complex, such as sodium-zinc triethyl, potassium-zinc methyldiethyl, and the like. Another effective class of reactants are certain reaction products of active metals and alkyl esters of polybasic acids.

The alkyl zinc reagents employed in reacting with the lead organoacid salt further include the identically dialkyl substituted compounds, such as diisopropylzinc, diethylzinc, dimethylzinc, dibutylzinc, diamylzinc, dihexyl-

zinc, diocetylzinc, or in the case of compounds with alkyl groups of four or more carbon atoms, the diisoalkyl compounds, or the tertiary alkyl compounds. The dialkylzincs having dissimilar alkyl substituents are frequently desirably employed such as methylethylzinc, ethyl-n-propyl zinc, isopropyl-n-butylzinc, isobutyl-3,3-dimethylbutylzinc, n-heptyl-n-octyl zinc and others. However, the process is not confined to the dihydrocarbon zinc compounds, it having been discovered that monoalkylzinc compounds are highly effective. Illustrative examples of such monoalkyl substituted zinc compounds are ethylzinc bromide, ethylzinc chloride, ethylzinc iodide, n-butylzinc bromide and the like. It is not essential that the organozinc compound be a purified and isolated zinc compound, but, in certain instances, reaction product mixtures having uncertain amounts of alkylzinc bonds are employable as reagents. For example, it has been recently discovered that metallic zinc can be reacted with diethylsulfate to yield a partially ethylated zinc-solid product. Other similar materials suitable for the process are the reaction products of zinc and alkyl derivatives of polyvalent acids, such as triethyl phosphate, dipropylhydrogen phosphate, et al. Also with the scope of acceptable alkylzinc compounds are the alkylzinc hydrides, such as ethylzinc hydride, n-butylzinc hydride, and the like. In addition to differently disubstituted dialkylzincs as illustrated above, mixtures of different identically disubstituted dialkylzincs are employable, such as, for example, mixtures of dimethylzinc and diethyl zinc. Similarly, complexes comprising zinc alkyls with an alkyl of a dissimilar metal are employable. Thus, complexes of dialkylzincs and alkali metal compounds are suitable.

As already mentioned, complex alkylmetal compounds, that is, those compounds having more than one metal in the compound are employable, typical specimens being the complexes having an alkali metal therein. The relatively pure monoalkyl compounds of the alkali metals can be employed, although these compounds generally are disadvantageous with respect to reaction efficiency because of their normally solid, insoluble character, whereas many of the other materials suitable are normally liquids at reaction conditions. Typical of the alkyl-alkali or alkaline earth metal compounds suitable in the process are ethyllithium, ethyl sodium, as well as the alkyl compounds having as low as one or up to about eight carbon atoms in the alkyl radicals.

Additional alkylmetal reagents for the process are the alkyl derivatives of beryllium and boron. The latter group of alkyl compounds includes not only the simple compounds having only one boron atom in the molecule, but also the alkyl-substitute derivatives of diborane B_2H_6 . Examples of these alkylboron compounds are triethylborine, triisobutylborine, trimethylborine, trimethyl diborane, tri-n-propylborine, et al. As with the other polyvalent metals, it is apparent from the above that it is not essential to the process that the alkylboron materials be fully alkyl substituted, but other substituents on the base metal are permissible unless they are degrading reactants.

By the process of this invention as much as 50 percent of the lead in the organic divalent lead salt is directly converted to tetraalkyllead and nearly 100 percent is converted when the organic tetravalent lead salts are employed. In the divalent lead embodiment of the process of this invention the unreacted lead is in highly active form as lead metal and is ideally suited for employment in the commercial process employing sodium-lead alloy or in that which proposes the reaction of metallic lead with an alkylating agent in the presence of magnesium and a catalyst. Conversely, the lead so produced by this invention can be treated and converted again to a lead salt of an organic acid and employed in making an alkyllead.

While this invention is adaptable to the production of tetraalkyllead compounds generally, wherein the alkyl radicals individually contain from one to about eight carbon atoms, for convenience in describing this invention

sometimes hereinafter specific reference will be made to tetraethyllead, the most widely known because of its use as an antiknock agent. Whenever, in the following description, this material is referred to, it is to be understood that other tetraalkyllead compounds can be made by this process. Further, for convenience in description below, reference may be made to non-lead alkylmetal compound. It will be understood that this refers to alkyl compounds of active metals of groups I-III-A having an electrode potential of over 0.3, such compounds being suitably used for treating the lead salts.

The particular details of carrying out any one embodiment of the process may vary appreciably from others, dependent upon the physical properties of the non-lead alkylmetal compound employed, and of course of the tetraalkyllead product released. A more or less generally applicable reaction procedure is initiated by providing a finely divided lead salt and feeding it into a suitable solvent or suspending medium in a stirred reaction vessel, said vessel being equipped with means for supplying and removing heat and introduction of liquids. The vessel is preferably equipped to handle moderate pressures in a sealed system, in many instances, atmospheric pressure operations being fully suitable. To the solution or suspension of the organic lead salt is introduced with agitation the non-lead alkylmetal reactant which may be diluted with a solvent or carrying medium. In many instances the reaction proceeds at moderate temperature and as the addition of the alkylmetal reactant proceeds mild refrigeration is applied to the reaction system until all the reactants are blended. To insure completeness of reaction, after such addition, external heating can be applied for a moderately long period of time after which the contents of the vessel are cooled to a convenient handling temperature and discharged into a recovery system. The recovery system employed depends partly upon the nature of the tetraalkyllead compounds produced and the nature of the by-product metal compound. In the typical manufacture of the lower tetraalkyllead compounds, such as for example tetraethyllead, wherein aluminum triethyl is reacted with lead acetate in the presence of a medium boiling hydrocarbon, it is convenient to discharge the reaction product mixture and to separate the solids, largely lead from the liquid components. The liquid phase can then be resolved by a multiplate vacuum fractionation to give a pure or relatively pure tetraalkyllead product and a separate hydrocarbon reaction medium stream.

While the above general procedure for conducting the process of this invention refers to a batch operation, in many instances improved operation can be obtained by employing a continuous reaction system wherein the two reactants are continuously and separately delivered in appropriate carrying media to a reaction zone and continuously discharging the products of the reaction to an appropriate recovery system.

When the process of this invention is conducted in the presence of an inert carrier liquid it is convenient to select the liquid so that at least one of the reactants is soluble therein. Thus, a controllable reaction is readily achieved, a distinct advantage of the process of this invention. Thus, many of the lead organoacid salts are at least partly soluble in hydrocarbons. For such reactants toluene, benzene, xylene, hexanes, kerosene and the like can be employed. Furthermore, when a normally liquid non-lead alkylmetal is to be reacted with such lead organoacid salts in such a hydrocarbon system, a homogeneous single phase reaction is frequently achieved, with precipitation during the course of the reaction of a non-lead metal salt corresponding to the lead salt employed. Recovery of the products from such a reaction can be effected by filtration of the aluminum byproduct and the tetraalkyllead compound dissolved in the hydrocarbon can be further processed for purification or employed as such.

When certain other non-lead alkylmetal reactants are

employed such as for example sodium aluminum tetraethyl, a two phase reaction system may result and in such instances the reaction is enhanced by employing such reactants in finely divided form and maintaining efficient agitation. In other cases, the non-lead alkylmetal may be a liquid substantially insoluble in any other liquid phase present. In such instances several liquid phases will be present.

In certain instances it is preferable to employ the tetraalkyllead compound itself as the inert diluent. Thus, the recovery of products is simplified and particularly in a continuous operation the materials handling problem and purification is minimized. This is particularly advantageous when employing non-lead alkylmetal compounds which are soluble in tetraalkyllead compounds, such a system, however, can also be employed when reacting certain of the mixed alkylmetal compounds or complexes such as for example the sodium fluoride-aluminum triethyl complex, the aluminum alkyl hydrides, aluminum sesquihalides, alkylzinc halides, and sodium zinc triethyl.

The examples given hereafter illustrate generally the numerous forms and embodiments of the process.

Example I

The equipment employed in the present example consisted of a stirred reaction vessel equipped with cooling and heating means as well as means for introducing the reactants to the reaction zone. To this reaction vessel was added 17.1 parts of finely pulverized and dried lead diacetate. The reaction vessel was purged with dry nitrogen gas and 100 parts of toluene was added followed by the addition of 4.09 parts of triethylaluminum. The suspension was stirred for a period of about 0.5 hour at which time the reaction temperature was slowly increased by external heating means to the reflux temperature of the solvent (110° C.) and maintained there for an additional period of 1 hour. At this time the reaction vessel was cooled to room temperature and the mixture was then filtered to remove the solid constituents. The filtrate thus obtained was washed with an equal volume of water and the organic layer was then transferred to a fractionating still for removal of the toluene and recovery of the tetraethyllead from the mixture. A 92% yield of high purity tetraethyllead was obtained.

Similarly, when trimethylaluminum, tripropylaluminum, tributylaluminum, trihexylaluminum and trioctylaluminum are employed in the process of the foregoing example, equally satisfactory yields of tetramethyllead, tetrapropylead, tetrabutylead, tetrahexylead and tetraoctylead are produced, respectively.

Example II

The procedure of Example I is repeated except that stoichiometric amounts of triethylgallium and lead diacetate are reacted in the presence of cyclohexane at atmospheric pressure and at a reaction temperature of about 80° to 95° C. for about 3 hours. A high yield of tetraethyllead is obtained.

Example III

Tetraethyllead is again prepared in high yield by reacting triethylindium with essentially a stoichiometric amount of lead tetraacetate in the presence of benzene as a dispersing medium under reflux conditions for a reaction time of about 2½ hours.

Example IV

Example I is repeated essentially as described with the exception that 15.5 parts of lead tetraacetate and 4.0 parts of triethylaluminum were employed. The reaction temperature was maintained between 0° and 10° C. for a total reaction time of 2.5 hours and at the end of which time the reaction mixture was worked up in an identical manner to that of Example I. A yield of tetra-

ethyllead of over 65%, based on the triethylaluminum employed was obtained with a formation of only a trace of metallic lead.

When trimethylgallium, tributylgallium, trihexylgallium, trioctylgallium, trimethylindium and triethylindium are employed in the process of the above examples equally as good yields of the corresponding tetraorganolead compounds are obtained.

Example V

The equipment employed in this example was essentially as described in Example I. To the reaction vessel was added 22.8 parts of lead diacetate and 50 parts of anhydrous toluene. The suspension was vigorously stirred under a nitrogen atmosphere and 5.8 parts of sodium aluminum tetraethyl was introduced into the reaction zone. The reaction mixture was heated to the reflux temperature (110° C.) and maintained there for a period of about 3 hours. The temperature was reduced to room temperature and the reaction mixture worked up in an identical manner to that of Example I to recover the tetraethyllead in a 73.5% yield based on the quantity of sodium aluminum tetraethyl employed.

Example VI

The procedure of Example V is repeated except that stoichiometric quantities of lead-tetraacetate and sodium aluminum tetraethyl are employed as the reactants. At a reaction temperature of about 85°-95° C. a high yield of tetraethyllead is obtained after a reaction period of about 4 hours. No metallic lead was formed.

Equally good results are obtained when alkyl metal complex compounds such as lithium aluminum tetraethyl, sodium aluminum tetrabutyl, sodium gallium tetraethyl, potassium gallium tetraethyl and sodium indium tetraethyl are employed in the processes of Examples V and VI.

Example VII

Again employing the procedure of Example I, tetraethyllead is obtained in high yield when diethylaluminumhydride is reacted with lead diacetate in essentially stoichiometric quantities in a toluene reaction medium. The reaction is conducted at the reflux temperature of toluene (110° C.) for a reaction period of about 6 hours.

Example VIII

The procedure of Example I is again repeated except that 44 parts of methylaluminodihydride and 325 parts of lead diacetate are suspended in 100 parts of benzene in the reaction vessel. The reaction is conducted for a period of about 8 hours at a reaction temperature of 50° C. and the tetramethyllead recovered therefrom in the manner of Example I. An excellent yield of tetramethyllead is obtained.

When diisobutylaluminum hydride, methylaluminum dihydride, methylgallium dihydride, isobutylindium dihydride, diisobutylgallium hydride, and diethylindium hydride are employed as the alkyl metal hydride in the process of Example VII equally as good yields of the corresponding tetraalkyllead compounds are obtained.

Example IX

In a similar process as is shown in Example I, 247.5 parts of ethylaluminum sesquichloride are introduced into the reaction vessel which contains 150 parts of xylene. The mixture is stirred at a rapid rate during the addition of 443 parts of lead tetraacetate, the reaction and the introduction being conducted under a blanket of dried and purified nitrogen. The reaction mixture is maintained at a temperature of about 90° C. for a total reaction time of about 3 hours at the end of which time the temperature is reduced to room temperature and the reaction mixture subjected to the separation steps described in Example I. A high yield of tetraethyllead is obtained.

Similarly, excellent results are obtained when dimethylaluminum chloride, methylaluminum sesquichloride, ethylaluminum sesquibromide, dimethylgallium chloride, ethylgallium sesquichloride, butylgallium sesquichloride, octylindium sesquichloride, and dipropylindium chloride are employed in the process of Example IX in the place of the ethylaluminum sesquichloride.

Example X

10 Excellent yields of tetrabutyllead are obtained when stoichiometric quantities of sodium aluminum tributylhydride and lead palmitate are employed in a similar process to that of Example I. The reaction is conducted at a temperature of about 40° C. for a reaction time of 15 about 8 hours and the product is recovered in the manner of Example I.

The use of potassium aluminum dioctyldihydride, potassium aluminum diethyldihydride, potassium gallium tripropylhydride, and lithium indium triethylhydride in the above reaction also results in excellent yields of the corresponding organolead compounds.

Example XI

This example demonstrates the suitability of employing 25 the complex salts of the alkylmetal compounds with sodium fluoride in the process of this invention. The equipment and procedures employed were similar to those of Example I except that 156 parts of sodium aluminum triethylfluoride and 325 parts of lead diacetate in the presence of 200 parts of cyclohexane were employed as the reactants. The reaction was conducted at a temperature of about 100° C. for a period of about 4 hours. At the conclusion of the reaction the temperature was reduced to room temperature and the reaction mixture 30 subjected to a fractionation process as described in Example I. An excellent yield of tetraethyllead was obtained. The sodium fluoride formed as a by-product in this process is recovered for use in the formation of additional sodium aluminum triethylfluoride.

40

Example XII

Example I is repeated essentially as described with the exception that tetraethyllead is employed as the diluent and the reaction temperature is 90° to 100° C. In this instance, the process is conducted continuously 45 by the continuous feeding of the triethylaluminum and lead diacetate to the reactor and withdrawing a slurry of solids in tetraethyllead from the reactor while leaving a heel of tetraethyllead sufficient to maintain the fluidity of the reaction mixture.

50

Example XIII

The process of Example I was repeated except that 40.4 parts of lead distearate and 4.1 parts of triethylaluminum were reacted together in 100 parts toluene 55 at reflux temperature. A 81% yield of tetraethyllead was obtained.

60

Example XIV

The suitability of using salts containing Pb-S bonding in the present process is demonstrated by this example. The procedure of Example I is repeated except that 246.8 parts of lead dithiofuroate and 70 parts of triethylaluminum are employed as the reactants in 300 parts of tetralin as a dispersing medium. The reaction is conducted at a 65 temperature of about 90° to 100° C. for a period of about 4 hours at which time the temperature is reduced and the product worked up in the manner of Example I. A very satisfactory yield of tetraethyllead is obtained.

70

Example XV

When the procedure of Example I is again repeated but employing 321.8 parts of lead phenolate and 98 parts of triisobutylaluminum in alphamethyl naphthalene as a solvent the results obtained are similar to those of 75 Example I. A high yield of tetraisobutyllead is obtained.

Example XVI

The process of Example I is repeated except that a mixed alkylaluminum compound is employed. Thus, stoichiometric quantities of methyldiethylaluminum and lead tetraacetate are employed in the procedure of Example I to give an excellent yield of alkylated lead products including tetramethylead, tetraethyllead, methyltriethyllead, dimethyldiethyllead, and trimethylethylead.

Equally good results are obtained when lead butyrate, lead formate, lead citrate, lead phenol sulfonate, lead salicylate, and lead naphthenate are employed as the lead salts in the processes of the above examples. As evident from the foregoing examples, it is customary to employ the reactants of any particular embodiment of the process in stoichiometric proportions. However, it will also frequently be found desirable to provide an excess of one or the other of the reactants according to specific circumstances.

The foregoing examples illustrate principally embodiments of the process wherein the non-lead alkylmetal compound is a compound of an aluminum type metal. Other alkylmetal compounds of polyvalent metals are also frequently effectively used as shown by the following examples.

Example XVII

A reaction vessel, provided with a vapor outlet and an internal agitator, was carefully dried and flushed several times with dry nitrogen. To the reaction space was added while agitating 40 parts of dry toluene, 11.5 parts of anhydrous lead diacetate and 4.32 parts of diethyl zinc. The foregoing charge ratio is equivalent to equimolar proportions of the lead acetate and diethylzinc.

Immediately on adding the diethyl zinc, the reaction mixture turned black and heat was evolved, showing that the reaction started immediately. Stirring was continued, after charging all components, for a one-hour period. At that time the temperature was raised to about 110° C., or enough to cause vaporization and refluxing of the toluene from an overhead condenser. This refluxing was continued for an additional period of about one hour.

Upon completion of the foregoing, the reacted mixture was inserted or poured into a volumetric calibrated container, and diluted to approximately twice the volume with benzene solvent. Aliquot portions of the reaction mixture were then analyzed and a yield of about 90 percent tetraethyllead was found.

The tetraethyllead is recoverable as a relatively pure product by filtration of the organic layer from the reaction product mixture, and by vacuum distillation or fractionation of the several components thereof.

Instead of the diethylzinc used in the foregoing example, equivalent amounts of other dialkylzinc compounds can be substituted. Thus, when diisopropylzinc or diethylzinc are substituted for the diethylzinc, similar high yields of tetraisopropylead and tetraoctylead are obtained.

Example XVIII

The procedure followed in Example XVII is repeated, except that about 7.8 parts of lead tetraacetate is used in place of the lead diacetate. A good yield of tetraethyllead from the lead tetraacetate converted is obtained.

As previously mentioned, it is not essential that a fully alkylated metal reagent be employed in treating the lead organoacid salt, as further shown by the following example.

Example XIX

Lead diacetate and ethylzinc hydride, in the proportions of about 24 parts of lead diacetate to 10 parts of ethylzinc hydride are reacted together in the presence of a substantial amount of benzene as a reaction medium. A high conversion of the lead diacetate to a good yield of tetraethyllead is obtained.

Instead of ethylzinc hydride, other monoalkyl derivatives of bivalent metals can be used. For example, suitable substitutes for the ethylzinc hydride include isopropylzinc hydride, amylzinc hydride and other monoalkyl zinc hydride compounds.

Similar compounds of other bivalent metals which are suitable as alkylating materials include the following: ethylmagnesium hydride, isopropylcalcium hydride, and n-hexylstrontium hydride.

10 In some instances, the alkylmetal compound is of unknown or uncertain composition but is characterized solely by the existence of alkylmetal linkages as in the following example.

Example XX

15 About 30 parts of zinc metal is heated with 71 parts of diethyl sulfate at a temperature of over 100° C. for a period of over one hour. A granular solid mass is produced; treatment of portions of this solid with isopropanol showed that it contained about 13 weight percent active ethyl groups.

20 The solid was mixed with lead diacetate in the proportions of 100 parts of solids and 75 parts of lead diacetate, in the presence of about 50 parts of toluene. After heating for about one hour at refluxing conditions, a production of about 20 parts of tetraethyllead was produced.

25 Frequently it will be desirable to employ an alkyl compound of an alkali metal, similarly to the reaction shown in the following example.

Example XXI

30 Sodium ethyl and lead diacetate are fed to a reaction vessel in approximately 2 to 1 molal proportions, concurrently with sufficient aromatic solvent to provide a thin slurry. The mixture is heated with stirring at about 105° C. for about three hours. A high conversion of the lead diacetate and a good yield of tetraethyllead are provided.

Example XXII

35 Lead diisobutyrate, 300 parts, and triethylborine, 100 parts, are reacted in the presence of about 500 parts of ethylbenzene at atmospheric pressure and with continuous stirring at 135° C. After continuing the reaction for several hours, a good conversion of the lead diisobutyrate and a high yield of tetraethyllead are obtained.

40 Not only are lead organo acid salts effective in supplying the sole lead source in production of tetraalkylleads, but, these reactants are also highly effective in conjunction with other reactions, providing that at least some bonds of a polyvalent metal are occupied by alkyl groups. Thus, a lead organo acid salt can be employed sequentially with an inorganic lead salt, for example, lead sulfide or lead oxide, used in proportion sufficiently to react some, but not all, of the alkyl groups of a polyalkyl metal compound, as is illustrated in the following examples.

Example XXIII

45 About 60 parts by weight of dry toluene was charged to a reaction vessel, and then about 12.3 parts of dry, powdered lead oxide. About 4.2 parts of triethylaluminum was charged, and the reaction mixture was heated to refluxing temperature and heating, with stirring, continued for 2.5 hours, and then about 6.3 parts of lead diacetate was added and the reaction continued for an additional hour. A conversion of 70 percent of the ethyl groups to tetraethyllead was obtained, or about 10 percent more than realized by reacting lead oxide solely.

50 When other lead organoacid salts are employed in a reaction step supplementing a previous reaction of a lead chalcogen with polyalkylmetal compound under such conditions that only a part of the alkyl groups are converted to tetraalkyllead compounds, similar increases in yield are provided.

55 A more preferred operation is to supply the lead source in the form of a double salt between the lead organo acid

salt and the lead chalkogen. These double salts can generally be prepared by reacting a solution of the lead organo acid salt with the lead chalkogen and removal of the solvent from the system to form the dry double salt. Double salts having varying proportions of lead organo acid salt to lead chalkogen are known and have been described in the literature.

Example XXIV

To a solution of 0.3 mole of lead acetate in about 25 parts of water was added 0.3 mole of lead oxide and 100 parts of benzene. The mixture was heated to distill off the benzene-water azeotrope leaving a white amorphous powder which was washed with petroleum ether and dried. The product was identified as the double salt, lead acetate · lead oxide.

About 30 parts by weight of dry toluene was charged to a reaction vessel followed by the addition of about 6.06 parts of the dried, powdered lead acetate · lead oxide double salt prepared above. The reaction mixture was heated to refluxing temperature and heating and stirring continued for one hour while concurrently adding a solution of about 1.68 parts of triethylaluminum in about 40 parts of toluene. Heating and stirring was continued for an additional hour after the addition of this material and the reaction mixture was then cooled to room temperature and the tetraethyllead recovered. A conversion of 78 percent of the ethyl groups to tetraethyllead was obtained.

When double salts of other lead organo acid salts and lead chalkogens are employed in similar reactions equally desirable increases in yield are obtained.

The pressure employed in the reaction vessel is not critical and usually ranges between about atmospheric pressure and the autogenous pressure created by the carrier liquid at the temperature employed.

The temperature required to initiate the self-sustaining reaction of this invention varies with the alkyllead compound being produced and the non-lead alkylmetal compound being reacted. In general it is preferred to employ temperature conditions under which the reactants and products are stable. Towards this end thermal stabilizers well known to the art, such as for example naphthalene and styrene, can be employed to permit the use of high reaction temperatures without concomitant decomposition of the alkyllead compounds. Generally temperatures between about -20° to 200° C. and pref-

erably between about 25° and 150° C. can be employed to initiate or conduct the present operation.

From the foregoing description and examples, it will be evident that the process of the invention is capable of a very large number of embodiments without departing from the scope thereof. Thus the mechanics of carrying out the reaction, including the temperature and pressure conditions; the physical state of the reactants, and the reaction medium employed, when one is used, can be greatly varied.

What is claimed is:

1. A process for manufacturing tetraalkyllead compounds which comprises reacting in an inert carrier liquid a lead salt of an organic acid wherein lead is attached to carbon through an intermediate chalkogen atom selected from the group consisting of oxygen and sulfur and wherein said organic acid contains from 1 to 25 carbon atoms inclusive with an alkyl metal compound of a metal having an electrode potential of more than 0.3 volt, and wherein each alkyl group of said alkyl metal compound contains up to 8 carbon atoms inclusive.
2. The process of claim 1 wherein the metal of said alkyl metal compound is a polyvalent metal.
3. Process of claim 1 wherein said lead salt is a salt of an acid selected from the group consisting of alcanoic, carboxyaromatic, and phenolic acids.
4. The process of claim 3 wherein said lead salt is lead diacetate.
5. The process of claim 3 wherein said lead salt is lead naphthenate.
6. The process of claim 3 wherein said alkyl metal compound is a group II metal alkyl.
7. The process of claim 6 wherein said group II metal alkyl is diethyl zinc.
8. The process of claim 3 wherein said alkyl metal compound is a group III-A metal alkyl.
9. The process of claim 8 wherein said group III-A metal alkyl is triethylaluminum.
10. A process for manufacturing tetraethyllead which comprises reacting lead diacetate with triethylaluminum in the molal proportions of about 1½ to 1 in the presence of an inert carrier liquid at a temperature between about 25 to 150° C.
